UNITED STATES PATENT OFFICE.

MORRIS EPSTEIN, OF NEW YORK, N. Y.

FOOT-GOVERNING DEVICE FOR SEWING AND EMBROIDERING MACHINES HAVING UNIVERSAL FEED MOTION.

Application filed July 14, 1924. Serial No. 725,817.

To all whom it may concern:

Be it known that MORRIS EPSTEIN, subject of the Government of Russia, residing at New York city, in the county of New York and State of New York, has invented certain new and useful Improvements in Foot-Governing Devices for Sewing and Embroidering Machines Having Universal Feed Motion, of which the following is a specification.

This invention relates to sewing and embroidering machines, and more particularly to machines of this character operating with universal feed-motion and in which the feed is governed by means of a crank handle positioned on the under side of the machine table top.

The general practice of operating power-driven machines of the character described is to conduct the crank handle for governing the feed with the right hand, to guide the material with the left hand, and to control the driving of the machine with one or both feet, the feet thus remaining comparatively idle while the hands bear the brunt of the work.

An object of the present invention is the provision of a device which shall enable the operator to control the driving of the machine with one foot, and to conduct the movement of the crank-handle governing the feed-motion with the other foot so as to leave both hands free to guide the material.

Another object of the invention is the provision of a device of the character described comprising few and simple parts, which may be readily attached to any sewing or embroidering machine having a universal feed-motion governed by a crank handle, which is comparatively inexpensive to manufacture and which serves to improve the efficiency of the control and operation of the machine to a high degree.

Other objects of this invention will in part be obvious and in part hereinafter pointed out.

The invention accordingly consists in the features of construction, combinations of elements and arrangement of parts which will be exemplified in the construction herein-after described and of which the scope of application will be indicated in the following claims.

In the accompanying drawing, in which

is shown one of the various possible illustrative embodiments of this invention,

Fig. 1 is a front elevational view showing in outline a machine of the character described, a motor drive and control therefor, and a device embodying the invention applied thereto;

Fig. 2 is a plan view of the stirrup guide plate;

Fig. 3 is a sectional view taken on line 3-3 of Fig. 2;

Fig. 4 is a front elevational view of the stirrup and swivel mounting therefor; and

Fig. 5 is a view partly in section of a modified form of a foot control device.

Referring in detail to the drawing, 10 denotes a sewing or embroidering machine having a universal feed-motion governed by a crank handle 11, said machine being of any standard make such as described in Patent No. 148,182 to E. Cornely, dated March 3, 1874. The machine 10 as seen in Fig. 1 is mounted on a top 12^a of a conventional sewing machine stand 12, the crank handle 11 for controlling the feed-motion being positioned on the under side of the top 12^a as is the general practice. For simplicity, machine 10 is shown to be driven by an individual motor equipment 13, the speed and operation of which is controlled by pressure on foot treadle 14 in the usual manner. It is to be understood that in case of group drive, which is quite common, the motor equipment 13 may be replaced by any form of clutch-control driving device installed in the well known manner.

A device for conducting the crank handle 11 governing the feed-motion by the foot instead of by the hand is designated as a whole in Fig. 1 at 15, and comprises a downwardly extending rod 16 which replaces the usual handle portion of crank handle 11, a stirrup 17 mounted on the lower end of rod 16, and guide plate 18 for engaging with downwardly projecting portion 17^a of stirrup 17.

The ends of rod 16 are preferably threaded to permit the proper adjustment of the rod 16 with stirrup 17 between crank handle 11 and plate 18, and said rod 16 may be rigidly secured to the upper end of the crank handle 11 by the lock nuts 19, as shown in Fig. 1. The stirrup 17 may be swivelly mounted in any suitable manner at the lower

end of the rod 16 and preferably has an anti-friction mounting 17^b as shown in Fig. 4, the upper portion of said mounting being fixedly secured to rod 16 by any suitable means as for example by a lock nut 20.

The guide plate 18, as shown in Figs. 2 and 3, is formed of an inner circular disc 21 and an outer annular disc 22 fitting therearound, there being a circular raceway 23 having a groove 23^a extending upwardly to the outer surface of plate 18 formed between said discs 21 and 22. Holes 21^a and 22^a formed in discs 21 and 22 respectively provide means for fastening guide plate 18 in position on the floor under the machine.

The projecting portion 17^a of the stirrup is adapted to extend down into the groove 23^a and is provided with a ball end 17^c to restrict the movement of the stirrup 17 to the path of the raceway 23.

The operation of device 16 is quite simple and as seen from Fig. 1, the left foot of the operator by pressure of treadle 14 controls the drive and speed of the machine 10, the right foot inserted in stirrup 17 governs the movement of universal feed-motion through crank-handle 11 and both hands of the operator are left free to guide the material being worked on.

If desired, by simply interchanging the relative position of treadle 14 and stirrup 17, the machine may be arranged to have the machine drive controlled by the right foot and device 15 by the left.

In Fig. 5 is shown a modified form of guiding connection for the lower end of stirrup 17 comprising a plate 24 on which a crank arm 25 is pivotally mounted preferably in a ball bearing 26. The outer free end of said arm 25 engages with a suitable downwardly extending stud 17^d and is arranged to guide the stirrup 17 in a circular path corresponding to the crank handle 11.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In combination, a sewing or embroidering machine having a universal feed motion and a device having foot receiving means adapted to move in a circular path for governing the feed motion.

2. The combination with a sewing or embroidering machine having a universal feed

motion of a revoluble foot operative device for governing the feed thereof, said device including a stirrup and relatively fixed means for guiding the stirrup in a closed circular path.

70

3. A sewing or embroidering machine having a universal feed motion and means for governing the feed thereof in combination with a foot operative device for controlling the movement of said means, said device including a stirrup and means for guiding said stirrup in a fixed path corresponding to the movement of the first said means.

75

4. A universal feed sewing or embroidering machine mounted on a table top, a crank handle for governing the feed positioned on the bottom side of the said table top in combination with means for receiving the foot of the operator depending from said crank handle for controlling the movements thereof in a circular path.

80

5. A universal feed sewing or embroidering machine mounted on a table top, a crank handle for governing the feed positioned on the bottom side of the said table top in combination with a foot operative device depending from said crank handle for controlling the movements thereof, said device including a stirrup and plate secured at a spaced distance below said machine for guiding said stirrup in a fixed path corresponding to the movement of said crank handle.

85

6. In combination, a power driven universal feed sewing or embroidering machine having foot means for controlling the speed of the machine and a device having a foot receiving means for governing the feed motion whereby both hands of the operator are left free to guide the material being worked on.

90

7. In combination, a power driven universal feed sewing or embroidering machine, means for governing the feed thereof, a treadle adapted to be actuated by one foot of the operator for controlling the speed of the machine, and a device having a circularly adjustable foot receiving means for controlling the movement of said feed means whereby both hands of the operator are left free to guide the material being worked on.

95

8. In combination, a power driven universal feed sewing or embroidering machine, means for governing the feed thereof, a treadle adapted to be actuated by one foot of the operator for controlling the speed of the machine and a foot operative device for controlling the movement of said means whereby both hands of the operator are left free to guide the material being worked on, said device including a stirrup and means for guiding said stirrup in a fixed path corresponding to the movement of the first said means.

100

9. A universal feed sewing or embroider-

130

ing machine mounted on a table top, a revolvable crank handle for governing the feed positioned on the bottom side of the said table top, a treadle adapted to be actuated by one foot of the operator for controlling the speed of the machine and a device having adjustable foot receiving means depending from said crank handle for controlling the movements thereof and adapted to be operated by the other foot of the operator, said device having relatively fixed means for guiding the movement of the crank handle in a closed circular path.

10. A universal feed sewing or embroidering machine mounted on a table top, a crank handle for governing the feed positioned on

the bottom side of the said table top, a treadle adapted to be actuated by one foot of the operator for controlling the speed of the machine and a device depending from said crank handle for controlling the movements thereof and adapted to be operated by the other foot of the operator, said device including a rod secured to the crank handle, a stirrup swivelly mounted on the lower end 20 of the rod, and a plate having means for engaging with the stirrup for guiding the latter in a fixed path corresponding to the movement of said crank handle. 25

In testimony whereof I affix my signature.

MORRIS EPSTEIN.
